UNITED STATES PATENT OFFICE.

JOHN W. BRANDT, OF ELYRIA, OHIO.

PLAYING BALL.

Application filed February 9, 1925, Serial No. 7,850.

My invention relates to playing balls and more particularly such playing balls as comprise an inflatable rubber bladder contained within a leather or like casing such as foot-
balls, basketballs and the like.

My invention has for an object the provision of a football that is more resilient than balls of the prior art with which I am familiar.

10 Another object of my invention is to provide a foot ball which is heavier, with the weight thereof uniformly distributed, than are the balls of the prior art.

15 Another object of my invention is to secure more resiliency and weight in a playing ball in a manner whereby the cost of manufacturing the ball will not be exorbitant.

Another object of my invention is to provide as an article of manufacture a resilient 20 weighting girdle adapted to be placed around the inflatable bladder of a playing ball such as a football, and which when the bladder is inflated, will be interposed between the containing casing and the bladder and distended by the inflation of the bladder.

25 Other objects of my invention and the invention itself will be better understood by reference to the accompanying drawings referred to in the following description comprised in this specification.

Referring to the drawings—

Fig. 1 shows a plan view of a section of rubber tubing employed in an embodiment of my invention as a weighting medium, and 35 to add to the resiliency of the ball;

Fig. 2 shows an end elevational view of the tubing placed over a football inflatable bladder, and with the bladder not inflated;

Fig. 3 shows a plan view of the bladder 40 slightly inflated and encompassed by the resilient tubing comprising a girdle for the bladder;

Fig. 4 shows a view of the football casing with the contained inflated bladder and interposed tubular girdle, certain parts of the casing being shown as broken away to permit a view of the inner parts;

Fig. 5 shows a longitudinal medial sectional view of a complete football comprehended in my invention; and

Fig. 6 shows a medial transverse section of the football of Fig. 5.

Referring to all of the figures in which like parts are designated by like reference 55 characters, at 1 I show an inflatable bladder made of sheets of thin rubber secured to-

gether in the usual manner at seams 2, there being two of such sheets placed face to face and secured together at the seams by a strip of like thin rubber material 3.

At 4 I show an inlet inflating tube for the bladder 1 carrying a flanged base 5 cemented to the bladder proper whereby air may be forced through the tube 4 into the interior of the bladder.

At 15 I show a tubular section of rubber herein illustrated as being a section cut from an automobile tire inner tube and which is substantially cylindrical in form, but departing slightly therefrom and having side 70 walls 6 and an opening through one of the side walls shown at 7, the opening 7 in the embodiment illustrated being disposed intermediate the ends of the tube 8 and 9 and preferably midway between such ends.

As illustrated in Fig. 2, and the other subsequent figures, in use the bladder 1 is placed within the tube 15 with the inflating tube 4 of the bladder passing through the opening 7 of the tubular girdle 15. In use such an 80 arrangement positions the tubular girdle 15 with reference to the inflatable bladder 1 and prevents longitudinal displacement of the one relative to the other. The tube 15 may be of differing forms, but preferably I 85 make it of substantially cylindrical form, or as illustrated, a form closely approximating the cylindrical form which may be obtained at the present time very cheaply in the form of sections of used rubber tire inner tubes, 90 these being obtainable in the right sizes and with such slight longitudinal curvature as to secure best results for the purposes herein set forth and accomplished by the ball of my invention.

In employing my invention in a playing ball such as a football, I place the superposed bladder and tubular girdle as shown in the figures within the leather casing of the ball, and inflate the bladder by forcing 100 air through the tube 4 to expand the bladder. The expansion of the bladder will likewise expand the tubular girdle 15 in lateral directions and will reduce the length thereof a certain amount commensurable with the degree of expansion. The tubular girdle 15 is purposely made of a sufficient length so as to compensate for the shortening due to transverse expansion when the ball is inflated. I find that such a ball constructed as described 105 is not only heavier than it would be were not the girdle 15 contained therein, but is

more resilient than were the girdle absent and the bladder merely inserted within the casing and inflated in the ordinary manner. I find that due to the rounded form of the inflated ball and the positioning of the openings 7 with reference to the inflating tubular stem 4 that the girdle when once positioned about the uninflated bladder contained within the casing illustrated at 10, and the bladder inflated that even where little or no care is used in positioning the tubular girdle with reference to the inflatable bladder and the casing interior, that the process of inflation brings about a positioning of the tubular interposed girdle relative to the bladder and the casing so that the weight on either side of the minor circumference of the ball will be balanced.

Having thus described my invention in a single embodiment, I am aware that the same may be practiced in varying forms departing from the form herein illustrated and described, but without departing from the spirit of my invention.

I claim:—

1. As an article of manufacture, a resilient weighting tubular girdle for playing ball inflatable bladders composed substantially entirely of rubber or like resilient material having a perforation in a side wall thereof intermediate its ends.

2. As an article of manufacture, a resilient weighting tubular girdle for playing ball inflatable bladders composed substantially entirely of rubber or like resilient material

having a perforation in a side wall thereof disposed half way between the ends thereof.

3. As an article of manufacture, a girdle for playing ball inflatable bladders made substantially entirely of rubber and having a perforation for the reception of the inflating tube of the bladder, such opening being disposed substantially midway of the length of the girdle, the girdle being substantially tubular in form and expansible when the enclosed bladder is placed within a leather or like casing to the rounded form of the casing next adjacent thereto.

4. In a playing ball, the combination with a relatively non-resilient casing, an inflatable bladder disposed therein and an interposed band of rubber encompassing the bladder, an inflating stem for the bladder, said band having a perforation through a side wall thereof, said stem passing through said opening.

5. In a playing ball, the combination with a relatively non-resilient casing, an inflatable bladder disposed therein and an interposed band of rubber encompassing the bladder, an inflating stem for the bladder, said band having a perforation through a side wall thereof, said stem passing through said opening, said bladder being substantially ellipsoidal in form when inflated and the stem being disposed midway between ends of the major axis thereof.

In testimony whereof I hereunto affix my signature this 31st day of January, 1925.

JOHN W. BRANDT.
